HAROLD E. WARMAN, OF MANISTEE, MICHIGAN.

BALANCED PUMP CASING.

Application filed October 4, 1921. Serial No. 505,305.

To all whom it may concern:

Be it known that I, HAROLD E. WARMAN, a subject of the King of Great Britain, residing in Manistee, in the county of Manistee, State of Michigan, United States of America, have invented certain new and useful Improvements in Balanced Pump Casings, of which the following is a specification.

My invention relates to pumps of what are known as the multiple-stage impeller type, wherein the fluid operated upon by the pump passes, first into a rotary impeller, usually of the central annular intake 15 centrifugal peripheral outlet form shown, mounted upon the driveshaft; and is delivered thence into the first stage pressure-chamber, communicating with the central annular inlet of a second similar impeller; 20 and is by it delivered into a second stage like chamber; the pressure generated in such second stage chamber being twice that of the pressure in the first chamber; and so on through a plurality of similar impellers of 25 any desired plural number into a like number of stage pressure-chambers, increasing in a like number of pounds per each stage; such impellers usually, but not necessarily, being mounted on the same shaft, and rotat- 30 ing at the same speed, whereby the pressure is increased as the liquid is passed through each succeeding impeller to the amount of the pressure generated in the first pressure chamber by the first impeller, in each suc- 35 ceeding stage. For instance, in a pump of the four-impeller type shown, if the initial pressure in the first stage pressure-chamber is, say 125 pounds per square inch, the pressure in the second chamber would be 40 250 pounds, in the third chamber 375 pounds, and in the out-let and final delivery out-let pipe, being the last stage pressure-chamber, 500 pounds, while the outlet of an eight stage pump of the same type would 45 have an interior pressure of 1000 pounds per square inch.

In the pumps of this type and character, working at such high pressures as 500 pounds per square inch or even higher, frequently the pressure is so great as to burst the pump casing, unless the same is made of excessive thickness and consequent great weight, which in many cases for many reasons is extremely undesirable.

The main object of my invention is to provide a pump of exceedingly simple and

cheap form of construction, wherein a balance pressure-chamber, or plurality of such superposed chambers, is provided between an outer peripheral wall and an inner 60 like wall; all of which annular concentric chamber, or chambers are each in free communication with one of the minor pressure-chambers, (usually that of the half pressure-stage, in this case that of 250 pounds per 65 square inch as shown in Fig. 1) into which balance-pressure chamber or chambers a portion of the liquid impelled in the early stages of its passage through the pump, enters to fill the same; whereby the pressure 70 exerted outward upon the inner face of the outer wall will in this case be only about one half ($\frac{1}{2}$) of what the succeeding last stage and outlet will have. And thus it will be seen that with an extremely light weight of 75 metal, a pump is provided that will be of long life, and having but little danger of bursting the pump-chamber walls by reason of excessive pressure.

My said invention is fully shown, described and claimed in the following specification, of which the accompanying drawing forms a part, wherein:

Figure 1 is a front view in elevation, taken in central vertical longitudinal section 85 of my said improved form of multiple-stage impeller pump, taken on the line 1—1 of Figs. 2 and 4 looking toward the left in the direction of the arrow in such Fig. 2;

Fig. 2 is an exterior end view of such 90 pump looking toward the right of such Fig. 1, also in the direction of the arrow therein.

Fig. 3 is an end view thereof taken in cross-section on the line 3—3 of Fig. 1, looking to the left in the direction of the 95 arrow; and

Fig. 4 is a like view of the same, looking in the same direction, taken in section on the line 4—4 of Fig. 1.

Referring to the drawing:—

My said improved balance pressure-chamber impeller-pump shown in its simplest form in Fig. 1, has the casing or housing A thereof, for purposes of assembling, etc., usually and preferably divided into an upper 105 and a lower part, being split horizontally along the central longitudinal line as indicated in Figs. 1 and 3, and comprises the outer imperforate wall 14 and the inner wall 13, which is provided at the center with an 110 annular slot 9, which is in free communication with the balance pressure chamber 10

which, as shown, also extends to the ends of the device so that the entire multiple impeller-pump-mechanism is entirely surrounded by such balance pressure-chamber. The 5 water or other fluid to be pumped enters through the inlet at the left-hand end of Fig. 1, and enters into the first impeller 6¹. And all such impellers are usually and preferably of the well known form shown in 10 Figs. 1, and 4, each comprising a hub-portion 16, formed integral with four axially staggered centrifugal fan-blades 11, also integral with the curved rear peripheral wall 16¹, the curved rear hub-portion, and the 15 straight axial front wall 17, whereby when rigidly secured upon the drive shaft B, usually by means of a spline-key 23 (Fig. 4), when such shaft B is rotated (preferably anti-clock-wise toward the left as indicated 20 in Fig. 4, when the fan-blades are staggered as shown) an intensive suction will be created in the inlet, and the pressure increased by each successive impeller the fluid or liquid passes through.

25 Formed integral with the inner peripheral wall 13, and of the substantial shape shown, and situated on the outlet side of the four-impellers shown are the guide members 7¹, 7², 7³ and 7⁴, having the fins 12 to direct 30 the water thrown centrifugally outward by the fan-blades of the impellers into the stage pressure-chambers 8¹, 8², 8³, and the outlet forming the last pressure chamber 8⁴; and the contour and curvatures of the walls 35 of 7¹, as well as 6¹, are such that the tortuous centrifugal path taken by the fluid is made easy for the flowing stream, and the friction reduced to a minimum, and for this reason the chambers 6¹, 6², 6³ and 6⁴ are 40 usually provided.

As above stated the double walled casing shown is split longitudinally and centrally into two parts, and is provided with the outwardly extending securing flanges 45 20, by which such two parts may be secured together by the securing bolts 21, and such flanges are cast integral with both the outer wall 14 and the inner wall 13, as clearly indicated in Fig. 4; but the interior flanges 50 are broken away at the point of the annular slot 9 so that the whirling stream of water in the stage chamber 8² will, by its centrifugal force, be forced into the annular and end balance pressure-chambers 10, so as to 55 entirely fill the same.

The casing A is usually of cast metal, iron or bronze, as are the other parts, while the main or drive shaft B is usually of rolled steel, and usually and preferably the journal-joints at the ends of the pump-shaft B, are made tight by means of a gland-packing 60 24.

The abutting faces of the inner and outer longitudinal securing flanges 20, are planed or ground to make a practically water tight

joint; and may be provided with an interposed packing or smeared with red-lead or other suitable substance, to render the joint tight before being placed in position. The lower portion of the casing is usually provided with suitable feet 25 of any desired plural number for supporting the same in position upon a suitable supporting floor.

It will be seen that by this arrangement, that if for instance the pressure generated 75 by the first impeller in the first stage pressure-chamber 8¹ is, say 125 pounds per square inch, that of the pressure generated in the second stage-pressure chamber 8² will be twice that or 250 pounds; that the pressure in the third stage pressure-chamber 8³ will be 375 pounds; while the pressure at the fourth stage pressure-chamber outlet will be 500 pounds; but that there being in the balance pressure-chamber 10, between the inner wall 13 and the outer wall 14, and also the outer end walls 25 and 26', the 250 pounds pressure of the water entering into such chamber or chambers 10, etc., through the slot 9, will cause an exterior pressure 80 upon the inner wall 13 of 250 pounds, thus balancing the interior pressure to a large extent of 125 pounds in 8¹ and the 250 pounds in 8², and also will provide an exterior pressure of 250 pounds on that portion of the inner wall surrounding the third stage chamber 8³, which will have an interior pressure of 375 pounds per square inch, and following the well known rule that closed 85 cylindrical casings will withstand a much 90 greater exterior pressure than they will interior pressure, by my invention herein first disclosed, a pump can be made of comparatively light weight that at the final stages 95 can carry safely, enormous fluid pressures 100 and still be of a minimum weight, a desideratum long sought but never prior to my 105 invention realized.

In some cases and especially in pumps of this type having a large plural number of 110 impellers by which great pressures are at last attained, in the final stages, additional balance pressure-chambers of substantially similar type may be provided exterior or adjacent to the balance pressure-chamber 10 115 shown, to any desired number as indicated in dotted lines in Fig. 1, thus forming a balance pressure chamber 10', exterior to the two last stage chambers 8³ and 8⁴, which chamber 10' is formed of what in full line 120 is the right hand end portion of the chamber 10, which, in this case is shown as being connected by the channel or plurality of channels indicated at the top and bottom of Fig. 1, by the dotted lines 28, and 29, such channel or channels being of any desired 125 number and being centrally located in a strong web cast integrally with the entire casing or housing structure A, or by another slightly different modification that portion 130

of the chamber 10 lying to the right of the peripheral slot 9 of the inner wall 13 may be closed by a circular wall piece 30, indicated in dotted lines in Fig. 1, and connected 5 with the pressure chamber 8³, or even with the outlet 8⁴, and it will be seen that by this latter arrangement, the difference between the outside and inside pressure of any stage chamber from first to last will ever be greater 10 than the pressure of the first stage in this case being 125 pounds per square inch, for 8² will be balanced in and out, 8³ will be in the same condition, and the outlet at 500 pounds will be balanced by the 375 pounds 15 pressure in the balance pressure 10', whereby only the wall 14 will have to be made of heavy metal.

It is very evident from an examination of the drawing and description that many 20 modifications and changes in the arrangement of the various elements making up and composing my new and improved form of stage pressure-pumps may be made without in any manner departing from the broad 25 scope of my invention herein first disclosed, described and claimed; and I do not intend to limit myself strictly to the exact form of impeller, nor to the arrangement thereof, herein shown and described; as I 30 consider that as set forth in the broad claims hereof I am entitled to protection of the broad principle of any number of balance pressure-chambers howsoever made or arranged, equalizing the interior and exterior 35 pressures, in all stage-pressure-pumps of every kind and character.

I claim:

1. In a device of the class described, a 40 balance pressure-chamber, exterior to the fluid impelling mechanism, in free communication with the flowing fluid at a point where its pressure is less than it is at the outlet.

2. In a device of the class described, a 45 balance pressure-chamber exterior to and entirely surrounding the fluid impelling mechanism, in free communication with the flowing fluid at a point where its pressure is less than it is at the outlet.

3. In a device of the class described, a 55 balance pressure-chamber exterior to and entirely surrounding the fluid impelling mechanism in free communication with the flowing fluid, by a substantially annular slot at a point where the fluid-pressure is less than it is at the outlet.

4. In a device of the class described, a 60 balance pressure-chamber, exterior to the fluid impelling mechanism, in free communication with the flowing fluid at a point where its pressure is substantially one-half of what it is at the outlet.

5. In a device of the class described, a 65 balance pressure chamber exterior to and entirely surrounding the fluid impelling

mechanism in a free communication with the flowing fluid chamber by way of a substantially annular-slot, at a point where the fluid-pressure is substantially one-half ($\frac{1}{2}$) of what it is at the outlet.

6. In a device of the class described, a plurality of fluid impeller-members in stage, each of which increases the pressure as it ejects the fluid; an imperforate outer casing-wall; and an inner perforate casing-wall 70 surrounded by the outer casing wall; whereby a balance pressure-chamber is formed between the inner and outer casing wall; and maintained under the fluid pressure of one of the lower pressure stage-chambers.

7. In a device of the class described, a balance pressure-chamber exterior to and entirely surrounding the fluid impelling mechanism; which mechanism comprises a plurality of centrifugal rotating impellers, 85 in stage, each impeller after the first receiving at its central inlet, the fluid under the increased pressure given to it by the immediately preceding impeller, and increasing the pressure with practically the 90 same amount as has its feeding impeller; and a passage in free communication with the flowing fluid at a point where its pressure is substantially one-half of what it is at the outlet, and in free communication at 95 the other end with the balance pressure chamber, or chambers.

8. In a device of the class described, a plurality of impeller members in stage, each of which increase the pressure as it ejects the fluid; the first impeller-member receiving the fluid from the inlet of the device delivering the same to its pressure-chamber at an increased pressure; and each succeeding impeller adding to the pressure at which it receives the fluid the equivalent of the pressure given to the fluid by the impeller first to receive it from the inlet; an imperforate outer casing-wall; and an inner perforate casing-wall surrounded by the outer casing-wall, whereby a balance pressure-chamber is, 100 or a plurality of chambers are, formed between the inner and outer casing-walls whereby the pressure in such exterior annular balance pressure-chamber, or chambers, 105 will be constantly maintained at a substantial portion of the pressure of the flowing stream at the outlet.

9. A device of the class described, comprising a double walled casing of substantially cylindrical form in cross section, longitudinally centrally divided into two parts, each having outwardly extending securing flanges formed integral with both the inner and outer walls; the inner wall 110 being broken away as well as the flange up to the inner surface of the outer wall on both sides; and the inner wall being annularly slotted circumferentially at or adjacent to the center, whereby free communica- 115 120 125 130

tion is made between the central water pressure chambers through which the water flows, and the two semi-circular balance pressure chambers formed between the outer-
5 wall and the inner centrally peripherally slotted wall at either end of such annular slot in the inner wall; whereby a pressure substantially equivalent to one-half ($\frac{1}{2}$) of the pressure at the moment in the outlet,
10 will be maintained in such balance-pressure-chamber or chambers at all times.

10. A device of the class described, comprising a plurality of fluid impeller members in stage, each of which increases the
15 pressure as it ejects the fluid; all of which are enclosed in a double walled casing of substantially cylindrical form in cross section, longitudinally centrally divided into two parts, each having outwardly extending
20 securing flanges formed integral with both the inner and outer walls; the inner wall being broken away as is also the flange up to the interior face of the outer wall on both sides; and the inner wall being annularly slotted circumferentially at or adjacent to the center where the flange is broken away; whereby free communication is had
25 between the substantially central water pres-

sure chamber through which the water flows, and the two semi-circular balance pressure 30 chambers formed between the outer wall and the centrally peripherally slotted inner wall at either end of such annular slot, so that a pressure substantially equivalent to one-half ($\frac{1}{2}$) of the pressure at the moment 35 in the outlet will be maintained in such balance pressure chamber, or chambers, at all times.

11. A device of the class described, having a plurality of staged pressure-chambers, 40 and also comprising a plurality of balance pressure-chambers, each exterior to one, or a sub-plurality of the staged pressure-chambers, each of which balance pressure-chambers is in free communication with one of the 45 staged pressure-chambers, whereby the outward pressure of the fluid in the stage pressure chamber interior to each balance-pressure-chamber is balanced by the inward pressure of the fluid in the balance pressure- 50 chamber.
